UNITED STATES PATENT OFFICE.

ROBERT H. PLASS, OF UPPER MONTCLAIR, NEW JERSEY.

SPRING WHEEL.

1,411,375.

Specification of Letters Patent.

Patented Apr. 4, 1922.

Application filed January 29, 1919. Serial No. 273,749.

To all whom it may concern:

Be it known that I, ROBERT H. PLASS, a citizen of Alsace, having declared my intention of becoming a citizen of the United States, residing in Upper Montclair, county of Essex, and State of New Jersey, have invented certain new and useful Improvements in Spring Wheels, of which the following is a specification.

10 The present invention relates to improvements in spring wheels for road or other vehicles, and has for its object to provide a device of this character which embodies novel features of construction whereby an outer 15 floating rim is correlated with the wheel hub in such a manner as to transmit the drive while allowing a certain relative movement of the floating rim with respect to the hub, said movement being resisted by springs 20 which serve to absorb all sudden shocks and jars and prevent the direct transmission thereof to the vehicle.

Further objects of the invention are to 25 provide a spring wheel of this character which can be readily constructed to carry ordinary or heavy loads, which is thoroughly dependable in its operation, and which will function in a smooth and noiseless manner without any excessive friction or binding of 30 the parts.

Still further objects of the invention are to provide a resilient wheel in which a cushion support is obtained for the floating rim by means of metallic springs, the springs 35 and associated link members for holding the floating rim and wheel hub in a correlated relation operating in an oil bath so that a smooth and noiseless action is obtained.

With these and other objects in view, the 40 invention consists in certain novel combinations and arrangements of the parts as will more fully appear as the description proceeds, the novel features thereof being pointed out in the appended claims.

45 For a full understanding of the invention, reference is to be had to the following description and accompanying drawings, in which:

Figure 1 is a side elevation of a cushion 50 wheel constructed in accordance with the invention, one set of side plates and the centering links being removed to show the springs and link actuated mechanism for automatically tensioning the springs to resist 55 a load upon the wheel.

Figure 2 is an edge view of the wheel, portions thereof being broken away and shown in section, and the section through the upper portion of the wheel being substantially on the line 2—2 of Figure 1. 60

Figure 3 is a front elevation of the wheel with the front casing removed to show the centering links which hold the floating rim against rotation.

Figure 4 is a detail plan view of one of 65 the spacing blocks which is interposed between the side plates of the hub, showing the manner of securing the block in position and also showing the spring actuated plunger of the block for holding the packing in operative position. 70

Figure 5 is a similar view showing a slight modification.

Corresponding and like parts are referred to in the following description and indicated 75 in all the views of the drawings by the same reference characters.

While many different mechanical means can be provided for carrying out the underlying idea of the invention, the particular 80 embodiment of the invention illustrated by the accompanying drawings will be described and explained for illustrative purposes. In these drawings the numeral 1 designates a wheel hub which may be of any 85 conventional construction, the outer end of the hub having a smooth flat face 1^a, while the inner end of the hub is provided with a brake drum 2, said drum being secured by bolts 3 to the hub flange 4. Rigid with the 90 wheel hub is a pair of spaced plates 5 and 6, the outer plate 5 fitting upon the outer end of the hub, while the inner plate 6 is engaged by the bolts 3, spacing collars 7 being arranged upon opposite sides thereof. The 95 bolts 3 also pass through a guard plate 8 which is arranged upon the inner side of the wheel and is clamped directly between the brake drum 2 and the outer spacing collar 7.

Secured to the inner face of the outer plate 100 5 at a point adjacent the hub is a bearing collar 9, and rotatable upon this bearing collar and also upon the inner spacing collar 7 is a ring 10. Projecting radially from this ring 10 at equidistant points on the periphery thereof are spaced lugs 11 connected by pins 12 which engage the ends of tension springs 13. These springs are arranged substantially tangentially with respect to the ring 10 and have their opposite ends con- 110

nected to pins 14 which connect the two plates 5 and 6 of the hub and assist in holding the said plates in a spaced relation. In the present instance there are six of these 5 springs 13 which are all arranged in a corresponding manner so that when the ring 10 is rotated in one direction upon its bearings all of the said springs will be simultaneously placed under tension.

10 The outer peripheries of the hub plates 5 and 6 are connected at intervals by spacing blocks 15 which are suitably riveted or bolted to the plates, and at intermediate points smaller spacing blocks 16 are interposed between the hub plates. One of these spacing blocks 16 is illustrated in detail by Figure 4, and it will be noted that one side thereof is bifurcated to provide flanges or arms 17 which are secured to the side plates by a 20 bolt 18 and screw 19, respectively. The screw 19 is locked against working loose by means of a set screw 20. Each of the spacing blocks 16 is provided with a transversely disposed plunger 21, as shown by dotted lines by Figure 4, the head of the plunger passing loosely through the hub plate 6 into engagement with a floating plate 22 which is provided upon the outer face thereof with packing 23. A coil spring 24 surrounds the 30 plunger 21 and normally forces the same against the floating plate 22, thereby holding the packing 23 in engagement with a plate which is carried by the floating rim, as will be hereinafter described. A slightly modified construction is shown by Figure 5, in which both of the flanges 17 of the spacing block 16 are secured to the plates 5 and 6 of the hub by bolts 25. In both forms of the invention the blocks serve both to hold 40 the hub plates 5 and 6 rigidly in a properly spaced relation, and also to provide a housing for the spring actuated plungers 21.

The lugs 11 of the ring 10 are connected to spaced links 26 which extend in opposite directions from the tension springs 13, the links of each pair being mounted upon the ends of the pins 12 so as to bear against the outer faces of the lugs. The free ends of each pair of these links 26 are connected by 50 a pin 27, the said pin also engaging a link 28 which is arranged in an angular relation to the pair of links and is connected to a pin 29. These pins 29 serve both as bearings for the outer ends of the links 28, and also 55 as connecting means between the hub plates 5 and 6. Each link 28 together with the corresponding pair of links 26 thus forms a set of toggle levers which are arranged in such a relation that when they are folded toward 60 each other the ring 10 will be rotated upon its bearings to place the springs 13 under tension. In the present instance the spaced links 26 are shown as having the intermediate 65 portions thereof offset outwardly, as indicated at 26°, said offset portions operating

within clearance openings 30 (see Fig. 2) in the hub plates 5 and 6. With the arrangement shown each of the tension springs 13 extends between a pair of the spaced links 26, and by offsetting the intermediate portions of the spaced links a maximum clearance space is thus provided for the springs without the necessity of needlessly increasing the space between the side plates 5 and 6.

70 The floating rim 31 is mounted upon a channel shaped ring 32, and link hangers 33 extend between the floating rim and the pivot pins 27 which connect the links 26 and 28. These link hangers 33 are engaged at their outer ends by pins 34 which pass 80 through bearing blocks 35 secured to the channel ring 32 by bolts 36, the inner ends of the link hangers engaging the pivot pins 27 on opposite sides of the links 28 and between the links 26. It will thus be noted 85 that the link hangers 33 are arranged in pairs, and these link hangers are formed in sections which are connected by knuckle joints 37. Coil springs 38 are applied to these knuckle joints and normally tend to 90 break the same, although when the link hangers are under tension the action of the coil springs 38 is overcome and they do not function. However, the moment the members 33 are subjected to compression the coil 95 springs 38 operate to break the knuckle joints 37 and overcome the dead center at the joint so that the two sections of the links can double or fold upon each other.

With this construction the load upon the 100 hub is suspended from the top of the floating rim by means of those link hangers 33 which happen to be above the horizontal axis of the wheel. The tension in these upper link hangers 33 will tend to swing the 105 free ends of the toggle link members 28 outwardly toward the rim of the wheel, thereby producing tension in the inner toggle members or links 26 and rotating the ring 10 upon its bearings to place the main 110 springs 13 under increased tension. The hub 1 and parts mounted thereon thus move downwardly a slight amount relative to the floating rim, the parts being correlated so that this relative motion is possible, although the floating rim is locked against rotation with respect to the hub. Upon this downward movement of the hub with respect to the floating rim those of the link hangers 33 which are at the top of the wheel 115 are placed under tension and support the load, operating as has just been described to rotate the ring 10 and increase the tension of the main springs 13 until equilibrium is produced between the springs and 120 the load. At the same time that the link hangers 33 at the top of the wheel are placed under tension, those link members 33 at the bottom of the wheel are correspondingly subjected to compression. The knuckle 125 130

joints 37 of these lower members 33 then function, the joints being initially broken by the action of the coil springs 38 so that the sections of the links 33 can double or 5 fold in the manner which is necessary to meet the conditions. There is thus no resistance offered to the downward movement of the hub with respect to the floating rim, other than that which is incident to the 10 friction of the parts and the increased tension produced in the main springs 13. The floating rim 31 is provided with side plates 39 and 40 which have a telescoping relation to the plates 5 and 6 of the hub. The inner side plate 39 has the outer periphery thereof riveted or otherwise secured directly to the channel ring 32, while the outer side plate 40 is secured to the corresponding side of the channel ring 32 by 15 means of a separate annulus 41. The outer side plate 40 of the floating rim is provided at points toward the inner periphery thereof with outwardly projecting pivot studs 42, said studs being shown as provided with 20 bases 42^a which are riveted or otherwise rigidly secured to the plate 40 (see Fig. 3). In the present instance there are three of 25 these pivot studs 42 which are arranged at angles of 120° apart. These pivot studs 42 are connected by toggle links 43 and 44 to 30 pivot bolts 45 which project outwardly from the hub plate 5 and provide a means for rigidly securing an outer guide plate 46 to the hub plate. When the floating rim and 35 hub have a concentric or normal relation, the pivot studs 42 and corresponding pivot bolts 45 are arranged on radial lines. An equalizing link 47 is pivotally connected at 40 to each of the inner toggle links 44, said 45 equalizing links extending between the guide plate 46 and the smooth outer end 1^a of the hub to a point substantially central of the hub, at which they are connected by a pivot pin 49. These equalizing links 47 slide 50 freely between the outer guide plate 46 and the outer end of the hub, being directed thereby in their lateral movements. By reference to Figure 3 it will be obvious that 55 these three sets of toggle links 43 and 44 prevent concentric rotation of the floating rim with respect to the hub, although the floating rim is free to have a limited radial and eccentric movement with respect to the hub. This is indicated by dotted lines, and 60 the three sets of toggle links 43 and 44 are operatively connected by the equalizing links 47 so that any movement of one set of the toggle links produces a movement in the other sets of toggle links. All of the 65 parts are thus tied together so that they cooperate and assemble to produce the desired result. These toggle links 43 and 44 and equalizing links 47 constitute the means for locking the floating rim and hub against 70 relative concentric rotation without inter-

ferring in any manner with the radial and eccentric movement of the floating rim with respect to the hub which is necessary to cause the main springs and spring operating links to function. 70

A cap piece 50 which is sufficiently large to house the hub centering mechanism comprising the toggle links 43 and 44 together with the equalizing links 47 and associated parts is applied to the outer side plate 40, 75 as indicated by Figure 2. This cap or casting 50 has a dust and oil proof connection with the said plate 5, and is imperforate so that it operates both to exclude dust and dirt and also to confine the oil with which the interior of the wheel is partially or entirely filled. 80

The inner side plate 39 of the floating rim is received between the before mentioned guard plate 8 and the packing 23 85 of the plate 22. This plate 22 is loose or rotatable upon one of the spacing collars 7, and is engaged by the before mentioned spring plungers 21 which tend to force the same outwardly and hold the packing 90 in a close engagement with the side plate 39 of the rim. Owing to the fact that the plate 22 is rotatable upon the spacing collar 7 the friction between the packing and side plate 39 will be reduced to a minimum. The 95 outer periphery of the guard plate 8 is flared outwardly at 8^a to receive an annular ring of packing 51 which is held in position by retaining means 52. The inclined inner wall of the flare 8^a serves to produce 100 a wedge action whereby the packing 51 is held in an effective engagement with the side plate 39. The oil or lubricant with which the interior of the wheel is partially or entirely filled is thus effectively confined within the interior of the wheel and loss thereof 105 prevented. At the same time dust and dirt is excluded from the mechanism, the outer packing ring 51 operating in a most effective manner to exclude coarse and heavy 110 dirt, while any fine particles which might by chance work beyond the outer packing 51 will be excluded by the inner packing 23. 115

A solid tire 53 may be fitted upon the floating rim 31, and the wheel is applied to 120 a vehicle in the same manner as an ordinary wheel. The centering toggle links 43 and 44 act in conjunction with the equalizing links 47 to lock the floating rim 31 against any appreciable rotation with respect to the hub 1. At the same time, the hub and floating rim are permitted to have a relative radial movement, and the load superposed upon the hub tends to force the same downwardly within the floating rim. This acts 125 through the link hangers 33 to bring the toggle links 26 and 28 into action with the result that the ring 10 is rotated and the main springs 13 placed under increased tension until the tension of these springs is 130

sufficient to resist the load. The load is equally distributed through all of the several main springs 13, instead of being transmitted from spring to spring as the wheel 5 rotates, and this is a very important feature, since it results in uniformity of action, eliminates noise, and prevents the needless wear and tear which is incident to bringing a series of springs rapidly into and out 10 of action as a wheel rotates. Not only is a yielding support provided for the load, but any shocks and jars incident to the passage of the vehicle over ruts or bumps upon the road surface will be effectively 15 absorbed, thereby protecting the vehicle against sudden shocks and jars.

It may here be observed that a fundamental distinguishing feature of the present invention resides in the use of three 20 pairs of toggle linkages for floatingly associating the rim with the hub, as illustrated in Figure 3. As described hereinbefore, each linkage comprises a pair of levers 43 and 44 which are pivoted at 42 and 25 45 respectively to the rim and hub portions of the wheel. One joint in each lever, namely 48, is constrained to movement on an arc of a circle having the centre 49, this constraint being effected in the particular 30 embodiment of the invention illustrated, by means of the equalizing links 47 joined at the common centre 49. It will be observed that the circle of which 49 is the centre does not remain stationary in the operation of 35 the wheel, but shifts about in its own plane. The driving torque is transmitted from the hub to the rim through the above-described system of linkages. The springs 13, however, serve to bias the rim to a position 40 centric to the hub and thus act to absorb shocks due to irregularities in the road.

While I have illustrated and described the principles of my invention as applied to spring wheel construction for vehicles, 45 manifestly said principles might readily be embodied in power wheels, pulleys and the like. Therefore, where I have used the terms "spring" or "resilient" wheel in my specification and claims, I wish to be distinctly understood as intending to cover and 50 include such other constructions wherein the said principles may be usefully applied.

Having thus described the invention, what I claim as new and desire to secure by 55 Letters Patent, is:—

1. A resilient wheel including a hub portion, a floating rim carried thereby, a ring rotatably mounted on the hub member, tensile springs arranged substantially tangential 60 to the ring to resist rotation thereof, and extensible means actuated by a radial movement of the floating rim relative to the hub to rotate the ring and tension the springs.

2. A resilient wheel including a hub por-

tion, a floating rim carried thereby, a ring rotatably mounted on the hub member, springs arranged to resist rotation of the ring, and means pivotally connected to the floating rim and to the ring for rotating the latter to tension the springs upon relative radial movement of the floating rim and hub portion. 70

3. A resilient wheel including a hub portion, a floating rim carried thereby, a ring 75 rotatably mounted on the hub member, springs arranged to resist rotation of the ring, hangers extending inwardly from the floating rim, and an operative connection between the hangers and the ring for rotating the latter to tension the springs upon relative radial movement of the floating rim and hub portion. 80

4. A resilient wheel including a hub portion, a floating rim carried thereby, a ring 85 rotatably mounted upon the hub portion, springs arranged to resist rotation of the ring, collapsible hangers extending inwardly from the floating rim and constructed to collapse under compression, and means 90 actuated by tension in the hangers, due to relative radial movement of the floating ring and hub portion to rotate the ring and tension the springs.

5. A resilient wheel including a hub portion, a floating rim carried thereby, a ring rotatably mounted on the hub portion, springs arranged to resist rotation of the ring, hangers extending inwardly from the floating rim and formed with brake joints 100 so that they will double up under compression, and means actuated by the hangers when subjected to tension due to relative radial movement of the hub portion and floating rim to rotate the ring and tension 105 the springs.

6. A resilient wheel including a hub portion, a floating rim carried thereby, a ring rotatably mounted on the hub portion, springs arranged to resist rotation of the ring, toggle links connecting the ring and hub portion, and hanger links extending inwardly from the floating rim and operatively connected to the toggle links for cooperation therewith to rotate the ring 110 and tension the springs when the floating rim is moved radially with respect to the hub portion. 115

7. A resilient wheel including a hub portion, a floating rim carried thereby, a ring 120 rotatably mounted on the hub portion, springs arranged to resist rotation of the ring, a series of toggle links connecting the ring and hub portion, and collapsible link hangers extending inwardly from the floating rim and operatively connected to the toggle links for cooperation therewith to rotate the ring and tension the spring when certain of the link hangers are subjected to tension due to relative radial movement be- 125 130

tween the floating rim and hub portion, said link hangers collapsing when acting under compression.

8. A resilient wheel including a hub portion, a floating rim carried thereby, a ring rotatably mounted upon the hub portion, springs arranged to resist rotation of the ring, a series of sets of toggle links connecting the ring and hub portion, and link hangers extending inwardly from the floating rim and operatively connected to the toggle links, said link hangers being formed in sections which are connected by a knuckle joint, so that the link hangers will collapse when subjected to compression, the link hangers cooperating with the toggle links when acting under tension due to relative radial movement between the hub portion and floating rim to rotate the ring and tension the springs.

9. A resilient wheel including a hub portion, a floating rim carried thereby, a ring rotatably mounted on the hub portion, springs carried by the hub portion and connected to the ring to resist rotation thereof, a series of sets of toggle links connecting the hub portion and ring, link hangers extending inwardly from the floating rim and connected to the toggle links, said link hangers being formed in sections which are connected by knuckle joints, so that they will double up under compression, springs applied to the knuckle joints for breaking the same, the link hangers being connected to the toggle links for cooperation therewith to rotate the ring and tension the springs when there is a relative radial movement between the floating rim and hub portion.

10. A resilient wheel including a hub portion, a floating rim carried thereby, means for locking the floating rim against concentric circumferential motion while permitting relative radial and eccentric motion thereof, said means comprising a plurality of sets of toggle links between the floating rim and hub portion, and equalizing links operatively connected to each other and to the different sets of toggle links, and means resisting radial movement of the floating rim relative to the hub portion.

11. A resilient wheel including a hub portion, a floating rim carried thereby, means for preventing concentric circumferential motion of the floating rim while permitting radial movement of the floating rim upon the hub portion, said means comprising a plurality of sets of toggle links between the floating rim and hub portion, and equalizing links pivotally connected to each other at substantially the center of the wheel at their inner ends and having their outer ends pivotally connected to the toggle links, and yielding means resisting relative radial movement of the floating rim and hub portion.

12. A resilient wheel including a hub portion, a floating rim carried thereby, a ring rotatably mounted on the hub portion, springs arranged to resist rotation of the ring, means actuated by radial movement of the floating rim relative to the hub to rotate the ring and tension the springs and means comprising toggle links for preventing concentric circumferential motion between the hub portion and floating rim. 75

13. A resilient wheel including a hub portion, a floating rim carried thereby a ring rotatably mounted on the hub portion, springs arranged to resist rotation of the ring, means actuated by radial movement of the floating rim relative to the hub to rotate the ring and tension the springs, means to prevent concentric circumferential motion thereof while permitting relative radial movement of the members, said means comprising a series of sets of toggle links connecting the floating rim and hub portion, and equalizing links operatively connecting the several sets of toggle links. 80

14. A resilient wheel including a hub portion, a floating rim carried thereby, a ring rotatably mounted on the hub portion, springs arranged to resist rotation of the ring, hangers extending inwardly from the floating rim and operatively connected to the ring to rotate the same and tension the springs upon relative radial movement of the hub portion and floating rim, means to lock the said members against concentric circumferential motion while permitting relative radial movement thereof, said means comprising a series of sets of toggle links connecting the hub portion and floating rim, and equalizing links operatively connecting the several sets of toggle links. 90

15. A resilient wheel including a hub portion, a floating rim carried thereby, a ring rotatably mounted on the hub portion, a series of sets of toggle links connecting the hub portion and ring, hangers operatively connecting the toggle links and floating rim to actuate the toggle links and rotate the ring and tension the springs upon relative radial movement of the hub portion and floating rim, means to prevent concentric circumferential motion of the members while permitting relative radial movement thereof, said means comprising a second series of toggle links connecting the floating rim and hub portion, and equalizing links operatively connecting the several sets of toggle links of the second set. 110

16. A resilient wheel including a hub portion, a floating rim carried thereby and movable radially relative thereto, corresponding telescoping side plates carried by the hub portion and floating rim, respectively, means cooperating with the telescoping side plates to obtain an oil tight connection, and yielding means arranged be- 125

6
tween the side plates and operable within an oil bath, said yielding means resisting radial movement of the floating rim.

17. A resilient wheel including a hub portion, a floating rim carried thereby and movable radially with respect thereto, corresponding telescoping side plates carried by the hub portion and floating rim respectively and spaced to provide a casing between the members, a closed cap applied centrally to one of the side plates of the floating rim and having an oil tight connection therewith, packing providing an oil tight connection between the opposite set of side plates, and yielding means arranged within the casing and operable within an oil bath, said yielding means resisting radial movement of the floating rim.

18. A resilient wheel including a hub portion, a floating rim carried thereby and movable radially thereto, spaced side plates upon the hub portion, spaced side plates carried by the floating rim and having a telescoping relation to the side plates of the hub, packing means interposed between one set of side plates, transversely arranged spring plungers holding the packing means in position, and yielding means arranged between the space between the side plates and operable within an oil bath, said yielding means serving to resist radial movement of the floating rim relative to the hub portion.

19. A resilient wheel including a hub portion, a floating rim carried thereby and movable radially relative thereto, spaced side plates upon the hub portion, spacing blocks between the side plates, side plates carried by the floating rim and having telescoping relation to the side plates of the hub, a packing plate interposed between one set of side plates, transversely arranged plungers slidably mounted upon the before mentioned spacing blocks and acting upon the packing plate to hold it in operative position, and yielding means arranged within the space between the side plates and operable in an oil bath, said yielding means resisting radial movement of the floating rim.

20. A resilient wheel including a hub portion, a floating rim carried thereby and movable radially relative thereto, spaced side plates upon the hub portion, corresponding side plates carried by the floating rim and having a telescoping relation with the side plates of the hub portion, a packing ring rotatable upon the hub portion and interposed between one set of side plates, spring plungers engaging the packing plate to hold it yieldably in operative position, and yielding means arranged within the space between the plates for resisting radial movement of the floating rim.

21. A resilient wheel including a hub portion, a floating rim carried thereby and mov-

able radially relative thereto, spaced side plates projecting from the hub portion, corresponding side plates projecting from the floating rim and having a telescoping relation to the side plates of the hub portion, a packing plate interposed between one set of side plates, yielding means holding the packing plate in position, a guard plate projecting from the hub portion, packing carried by the guard plate and engaging the outer side of the pair of side plates provided with the packing plate, and yielding means arranged within the space between the side plates for resisting radial movement of the floating rim.

22. A resilient wheel including a hub member and a floating rim member, a ring rotatably mounted upon one of the said members, springs arranged tangential to said ring to resist rotation thereof and extensible means pivotally associated with said floating rim and actuated by a radial movement of the floating rim relative to the hub member to rotate the ring and tension the springs.

23. A resilient wheel including a hub member and a floating rim member, a ring rotatably mounted upon one of the said members and arranged concentric to the hub, springs arranged to resist rotation of the ring, and hangers extending between the two members and operatively connected to the ring for rotating the latter to tension the springs upon relative radial movement of the floating rim and hub member.

24. A resilient wheel including a hub member and a floating rim member, in combination with a ring rotatably mounted upon one of the said members and arranged concentric to the hub, springs arranged to resist rotation of the ring, and collapsible hangers extending between the hub member and the floating rim member and arranged to collapse under tension, said hangers being operatively connected to the ring to rotate the same and tension the springs upon relative radial movement of the floating rim and hub.

25. A resilient wheel including a hub member and a floating rim member, in combination with a ring rotatably mounted upon one of the said members, toggle links connecting the ring and the other member, springs arranged to resist rotation of the ring, and hangers extending between the hub member and floating rim member and connected to the toggle links for cooperation therewith to rotate the ring and tension the springs when the floating rim is moved radially with respect to the hub member.

26. In combination, a rim portion, a hub portion, toggle links for associating the rim portion with the hub portion, means for constraining a point on each of said links to movement on an arc of a circle described

about a common central point, and resilient means associated with said toggle links for biasing said rim portion to a position concentric with said hub portion.

5 27. In combination, a rim portion, a hub portion, toggle linkages for associating said portions, each of said linkages comprising a lever pivotally connected to the hub portion, means for constraining a point on each of 10 said levers to movement on an arc of a circle common to all of said points, and resilient means for biasing the rim portion to a position concentric to the hub portion.

28. In combination, a rim portion, a hub portion, resilient means for biasing said rim 15 portion to a position concentric to the hub portion, and mechanism for transmitting driving torque from the hub portion to the rim portion, said mechanism comprising a plurality of toggle linkages and being independent of said resilient means so that substantially no load is put on said resilient means by the torque transmitting operation of said mechanism. 20

ROBERT H. PLASS.
